[57] CLAIM

The ornamental design of a combined twine bobbin and twine therefor, as shown and described.

DESCRIPTION

FIG. 1 is bottom and side perspective view of a combined twine bobbin with twine therefor of my new design;

FIG. 2 is an elevation view;

FIG. 3 is a bottom view;

FIG. 4 is a top view;

FIG. 5 is a side edge view;

FIG. 6 is a front face view of the twine bobbin free of the twine;

FIG. 7 is a perspective view of the bobbin of FIG. 1 without twine wound thereon; and,

FIG. 8 is a side edge view thereof.

FIG. 1

FIG. 2
